UNITED STATES PATENT OFFICE.

VINCENZO LALLI, OF ST. ALBANS, NEW YORK.

HOD.

Application filed December 13, 1926. Serial No. 154,513.

The present invention relates to improvements in hods, and refers more particularly to a hod for carrying mortar, although it may be used for the general purposes to which hods are put.

An object of the invention is to provide a hod which will be substantially leak-proof, durable and resistant to the rough usage given these devices, of simple construction and inexpensive manufacture.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of an improved hod constructed according to the present invention.

Figure 2 is an end elevation thereof.

Figure 3 is an opposed end elevation.

Figure 4 is an enlarged fragmentary section taken on the line 4—4 in Figure 5.

Figure 5 is a side elevation with parts broken away and parts shown in section.

Figure 6 is a perspective view of one of the sides.

Figure 7 is a perspective view of the end or back.

Figure 8 is a similar view of the connecting rail, and

Figure 9 is also a perspective view of a cross brace employed.

Referring more particularly to the drawings, the hod is shown as composed in general of the sides 10 and 11, the end or back 12, the connecting or joining rail 13 and the handle 14 part only of which is shown in the drawings. The sides 10 and 11 are assembled in V-shape formation upon the joining rail 13 and the hod is open above and at one end in accordance with the prevailing construction.

The particular construction of each side member is shown in Figure 6. The side is made from wood or other appropriate material substantially rectangular in cross section and of appropriate thickness to permit of receiving near one end the transversely extending groove 15. This groove extends completely across the side member, is preferably generally parallel with the ends thereof, and is located close to the end of the hod having the back member 12, the

side edges of which are intended to be received into the grooves 15. The side walls 16 of the grooves are, therefore, preferably made at substantially right angles to the bottom wall and present abrupt shoulders taking against the side edges of the back member 12 to bind said back member against any casual longitudinal movement in the hod. The back member 12 conversely spaces the sides 10 and 11 and prevents collapse thereof.

Still referring more particularly to Figure 6, the sides are formed with beads or tongues 7 extending along the lower edges 70 and intermediate of the lower edges, whereby to leave the shoulders 18 and 19 at opposite sides of the tongues, which tongues are preferably at their free or exposed ends rounded or curved. The tongues or beads 75 are also of substantial thickness and are uniform in cross section throughout, except where the groove 15 intersects such tongue, the tongue being cut away at one side to permit of uniformity in the cross section of the 80 groove. It will be noted that the shoulder 18 at the one side is preferably narrower than the shoulder 19 at the outside edge as this outside shoulder will sustain most of the weight of the side piece and a substantial area of contact is consequently desired. The side piece in Figure 6 is further modified by the production therein of the slot 20 made diagonally therethrough between the groove 15 and the near end of the side 85 piece. This slot 20 is also made near the upper edge of the side piece. The purpose of the slots 20 is to receive the cross brace 21, shown more particularly in Figure 9, as having the beveled ends 22 and 23 to agree with 90 the outside surfaces of the side pieces 10 and 11, into the planes of which said beveled brace ends project through the slots 20. The brace 21 is secured, as by the nails or other fastenings 24, to the back or end piece 12, and as by the fastenings 25 to the ends 95 of the side pieces 10 and 11. The brace 21 thus extends outwardly of the back piece 12, this back piece being as usual extended up above the side pieces 10 and 11 and having its upper edge rounded.

The end piece 12, is shown more particularly in Figure 7, as being generally rectangular in form, except for the rounded upper edge and for the truncated lower apex 110 26, which is adapted to fit in the transverse groove 27 made in the upper surface of the

joining rail 13, which is shown to advantage in Figure 8. This joining rail is also of generally rectangular form, but having a lower removed or truncated end forming a flat shoulder 28. The upper surface of the rail is provided with an intermediate flattened portion 29 forming the base of the hod. This base portion 29 is considerably narrower than the width of the upper portion of the rail 13 and at the immediate sides of the base portion 29 are the beveled shoulders 30 to receive the narrow shoulders 18 at the lower edges of the side pieces. Outwardly of the beveled shoulders 30, the rail is cut away to form the longitudinal grooves 31 for receiving the tongues 17 of the side pieces. The grooves 31 will be of complementary form and in the case shown rounded at the base portions to receive the rounded free edges of the tongues 17. Outwardly of the grooves 31 are the outer shoulders 32, which are at a lower level than the base 29, and the upper edges of these shoulders 32 are diagonal or inclined to receive the larger outer shoulders 19 at the lower edges of the side pieces.

As shown in Figures 2 and 4 a snug fit is had between the tongues 17, grooves 31 and the shoulders at opposite sides of the tongues both upon the joining rail and the side pieces. A tight joint is thus provided avoiding any leakage between the joining rail and side pieces.

The end piece 12, as shown in Figure 4, is received along its downwardly convergent edges into the grooves 15 of the side pieces and at its base into the alining transverse groove 27 in the joining rail 13. In this position it is held and bound partly by the cross brace 21 and additionally by the metal strap 33, which is passed about the upper exposed curved edge of the end piece 12, down upon the outer faces of the side pieces 10 and 11 and beneath the joining rail 13. The metal strap 33 is nailed or otherwise secured to the various parts it embraces and it serves to effectively hold the parts together. The end piece 12, by its engagement with the shoulders 16, will prevent any longitudinal creeping movement of the side pieces and by its engagement in the similarly formed groove 27 in the rail 13 will prevent any relative creeping of the rail with respect to the side pieces which might open up the joint between these parts and result in subsequent leakage. The end piece 12 is also held by the side pieces against inner or outer movement. The engagement of the cross brace 21 in the diagonal slots 20 also serves to prevent any rocking movement of the side pieces upon the tongues 17, which might also loosen the joint at the base of the hod and permit leakage.

This purpose is further subserved by the metal straps or braces 34 extending up along

and riveted or otherwise secured to the intermediate portions of the side pieces 10 and 11, and also extending down along the sides of the handle 14, being also riveted or otherwise secured to said handle. A shoulder 70 receiving strip 35 is secured between the handle 14 and the closed end of the hod, such shoulder piece being fastened to the lower flat edge 28 of the joining rail 13. At the opposite side of the handle is disposed a 75 diagonal brace 36 having one end 37 turned down along the handle and secured thereto, while the upper end of the brace meets the bottom flat edge 28 of the joining rail at a point considerably inward of the open end 80 of the hod. Thence the brace passes along and in contact with said lower flat rail edge 28 providing a shank 38, the terminal end 39 of which, is shown in Figure 3, as being bent up at the open end of the hod and overlapped upon the end of the rail 13 to which it is secured as by the screw or other fastening 40. The open edges of the hod are preferably reinforced by the metal wear plates 41 secured, as by the fastenings 42, to the 90 edges of the side pieces 10 and 11 and the brace terminal 39 overlaps the lower convergent edges of these wear plates or strips and prevents them from becoming bent out or distorted.

The hod is used in the customary manner being supported upon the shoulder and carried and balanced by the handle 14. It will be found extremely useful for carrying fluid material, for instance mortar, and will not 100 be susceptible to the leakage now generally encountered in hods of standard construction. This leakage is wasteful and expensive and seeps into the portions of the hod rotting the same and decreasing the lift of 105 the hods.

While the tongues 17 are shown as having rounded ends, it is conceivable that these ends might be made square or of other configuration; the grooves into which the same 110 fit, being of course altered to conform with the shape given said tongues.

It is obvious that various changes and modifications may be made in the details of construction and design of the above specifically described embodiment of this invention without departing from the spirit thereof, such changes and modifications being restricted only by the scope of the following claims:—

What is claimed is:—

1. A hod comprising a joining rail having an upper flat portion serving as a base for the hod, narrow shoulder portions at the sides of said flat portion, longitudinal grooves outwardly beyond said narrow portions, and wider shoulder portions outwardly beyond said grooves, side pieces assembled upon said rail and having longitudinal tongues for fitting into said grooves, and 130

narrow and wide shoulders at the inner and outer sides respectively of said tongues for engaging against the respective shoulders on said rail, said wider shoulder portions 5 forming thick walls for the outer portions of the longitudinal grooves and acting to receive and support the outside portions of the tongue, an end piece fitted between said side pieces, and means for binding the parts 10 together.

2. A hod comprising a narrow elongated joining rail having a flat top surface portion serving as a base for the hod with its side edges cut off diagonally, said side edges having longitudinal grooves formed therein, said grooves being situated closer to the flat surface than to the outside edges of the joining rail whereby to provide narrow inner and broader outer shoulders, the direction of 15 depths of the grooves being at substantially right angles to the diagonal plane passing 20

through the inclined shoulders, sides having narrow and wide shoulders to fit against the diagonal shoulders on said rail and also having transverse grooves and diagonal slots 25 with tongues projecting from the lower ends of said side pieces for fitting into the grooves of said joining piece, said side pieces also having shoulders for engaging against the shoulders of the joining rail, said joining rail also having a transverse groove to align with the grooves in said side pieces, an end piece having its side edges fitting in the grooves in said side pieces and its lower end fitting in the transverse groove in said rail, means for securing said side pieces, end piece and rail together, and a brace fitted 30 to the outside of said end piece and having diagonally cut ends lying in said slots of the side pieces and secured to said side pieces. 35

In testimony whereof I affix my signature.
VINCENZO LALLI.
